MARINE DISTRESS SIGNAL

Herman S. Teetor, 30 15th Ave. S.,
Naples, Fla. 33940

Filed Dec. 27, 1968, Ser. No. 15,129

Term of patent 14 years

Int. Cl. D29—02

U.S. Cl. D72—1

Fig. 1.

FIG. 1.

FIG. 2.

FIG. 1 is a perspective view of a marine distress signal showing my new design;

FIG. 2 is a top plan view of the signal;

FIG. 3 is a side view of the signal when viewed in any of the directions indicated by the arrows 3 in FIG. 2; and

FIG. 4 is a side view of the signal when viewed in any of the directions indicated by the arrows 4 in FIG. 2.

The dominant features of my design are shown in full lines.

I claim:

The ornamental design for a marine distress signal, substantially as shown and described.
